UNITED STATES PATENT OFFICE.

HAROLD SPORN, OF BROOKLYN, NEW YORK.

DESIGN FOR A BATHING BAG.

Application filed June 10, 1927. Serial No. 22,387. Term of patent 3½ years.

To all whom it may concern:

Be it known that I, HAROLD SPORN, a citizen of Austria, residing at Brooklyn, in the county of Kings and State of New York, have invented a new, original, and ornamental Design for a Bathing Bag, of which the following is a specification, reference being had to the accompanying drawing, forming part thereof.

In the drawings:—

I claim:—

The ornamental design for a bathing bag, as shown.

HAROLD SPORN.
